UNITED STATES PATENT OFFICE.

JOHN ATKINSON, OF NEW YORK, N. Y.

WELL-BORING AND ROCK-DRILLING MACHINE.

SPECIFICATION forming part of Letters Patent No. 246,446, dated August 30, 1881.

Application filed February 19, 1881. (No model.)

To all whom it may concern:

Be it known that I, JOHN ATKINSON, of the city, county, and State of New York, have invented certain new and useful Improvements 5 in Well-Boring and Rock-Drilling Machines, of which the following is a specification.

This invention relates to that class of drilling or boring machines designed to bore into the earth through rocks or other strata for

10 the formation of Artesian wells, or for mineral prospecting or other purposes, and which employ diamond-studded drills with a rotary motion.

It also relates to machines of this kind in 15 which the rotary drilling-spindle is revolved by an engine directly applied, and in which the spindle is mounted on a vertical sliding frame supported on hydraulic pistons which control the feed or up-and-down movement of the drill.

20 My improvements consist in a special manner of arranging and connecting the engine and drill-spindle with relation to each other, in the manner of applying and controlling the water-pressure on the hydraulic pistons, and in 25 certain other details whereby important advantages are secured, hereinafter fully set forth.

In the accompanying drawings, Figure 1 gives a front elevation of my improved machine. Fig. 2 is longitudinal elevation, partly 30 in section; and Fig. 3 is a fragmentary sectional plan on line *x x* of Fig. 1.

Similar letters of reference indicate corresponding parts.

The bed-plate or base of the machine is indicated by *a*, and in plan view has the form 35 of a **T**, the cross bar or head of the **T** being at the front end, while the stem extends backward. (See Fig. 3, where the stem is broken off.) From the head of this base and at each 40 corner thereof, two standards, *b b*, arise; and closely adjoining these, on the inner side, are two hydraulic cylinders, *c c*, fixed at the base to the bed-plate and at their upper end to the sides of the standards.

45 *d e f* indicate a vertically-sliding frame mounted between said standards and cylinders, and consists of two cross-heads, *d e*, joined by four rigid rods, *f*, the lower cross-head, *d*, being guided between the cylinder on guides 50 *g g* fixed to the inner sides thereof, while the upper and broader cross-head is guided on guides *h h* formed on the upper part of the standards *b b*. The cylinders *c c* are provided

with tight-fitting hydraulic pistons, as indicated by dotted lines in Fig. 1, and rods extend from these pistons through the heads of the cylinder and connect rigidly to either arm of the cross-head *e*, thus operatively connecting the said piston with the sliding frame. A rigid cross-bar, *i*, spans the space between the cylinders and is fixed to each cylinder-head, as seen best in Fig. 1.

k indicates the rotary-drilling-spindle to which the power is imparted, which extends centrally through the cross-heads of the sliding frame and through the fixed cross-bar *i*, and is supported near its lower end on the lower cross-head by a grooved rim or head, *k'*, which rests on a circle of balls, *l*, free to roll on a circular track in a cavity of the lower cross-head, as seen best in Figs. 2 and 3. The spindle is, as usual, tubular or hollow throughout, to admit the coupled lengths of tubing *t*, which descend into the well-bore, and are terminated at the lower extremity with the diamond-studded bit or drill, in the usual manner. Each end of the spindle which projects beyond the cross-heads *d e* is formed to act as a chuck 75 to firmly grasp the piping *t t* and make a secure driving-connection therewith, yet admit of being readily loosened when required to insert an additional length of pipe as the boring proceeds, or to allow of raising or lowering the piping, as circumstances may require. I prefer to form these chucks simply by slitting the 80 tubular spindle with two or more slots, as seen in Fig. 2, and clamping the slotted end upon the piping by two jaws joined by screw-bolts similar to the halves of a journal-box, as shown best at *m m*, Fig. 1; but any other suitable form of chuck may be used. The upper 85 end of the spindle just below the upper chuck is guided in a journal-box, *n*, in which it is free to turn; but this journal-box does not support any of the weight of the spindle and its 90 attached tubing and drill, as this weight is all supported on the bearing *k l* on the lower cross-head; and as this bearing is on freely-rolling balls or rollers, the rotary movement of the spindle is thereby rendered very smooth 95 and easy, and this feature constitutes one of the minor parts of my invention. The spindle is revolved by the driving-sleeve *o*, which encircles the spindle below the upper cross-head, and is itself free to turn in the cross-bar *i*, but 100 is restrained from endwise movement therein

105

by the hub of a large spur-pinion, P, to which it is fixed, and by a shoulder on the lower end of the sleeve, as fully shown in Fig. 2. This sleeve is rotatively connected with the drill-spindle by the usual device of a groove on the one part engaging a feather on the other, which at the same time freely allows the up-and-down motion of the spindle.

A indicates the motor or engine by which the spindle is revolved, for which I prefer a steam-engine. In the case illustrated this is an ordinary form of horizontal steam-engine, but, as will be observed, is turned, so to speak, on its side, so that its crank-shaft becomes vertical and parallel with the drill-spindle. The lower end of the shaft hence revolves in a step fixed in the bed-plate, and above the step the fly-wheel q is fixed to the shaft and revolves close to the bed-plate. The upper end of the shaft revolves in an ordinary form of journal-box, r, and is finally terminated with a large spur-gear wheel, s, which meshes with the driving-pinion p, as shown fully in Fig. 1. This arrangement of parts, as will be now observed, is particularly compact and direct-acting, for the peculiar position of the engine brings its crank-shaft directly behind the spindle and sliding frame, which is advantageous and enables it to gear with the spindle by direct spur-gearing. Furthermore, the end of the shaft is supported in a step, which insures easier running than would be the case with horizontally-disposed journal-boxes. Were the engine placed in the usual position with the crank-shaft horizontal, it would not only occupy a greater floor-space, requiring the bed-plate of the machine to be made larger and heavier, but it would be necessary to employ bevel-gearing to connect it with the spindle, which would not only be less compact and direct, but also less smooth and accurate in its running, as it is well known that spur-gearing can be made with greater accuracy, possesses greater strength, and runs more smoothly and with less vibration than is the case with bevel-gearing.

In lieu of spur-gearing, chain-gearing may be used; or, if desired, in some cases direct belting may be employed; but positive spur-gearing is preferable.

Steam is supplied to the engine A through the pipe u from any suitable source, and a branch steam-pipe, o, extends from the former to the propelling-cylinder of a hydraulic-pressure pump, B, which may be of any suitable kind.

The suction-pipe a' of the pumping-cylinder dips into a water-tank, b', adjoining the base of the machine, while the discharge-pipe c' extends through the hollow of the bed-plate and discharges or opens into the base of each of the cylinders e e, as shown by dotted lines in Fig. 1. By this arrangement it will be seen that the hydraulic pressure is applied beneath the pistons, thus tending to lift the same, and with them the sliding frame d e f and drill-spindle, and the machine is so designed that

the pump B is worked constantly to exert a constant upward pressure on the pistons, which will always tend to lift the sliding frame and spindle, while the downward motion of the frame and spindle is effected by their own gravity by allowing a more or less free escape of the water from beneath the pistons. This method secures many advantages over the system of hydraulic feeding heretofore used, where the pressure is applied to force down the spindle and where the pump is thrown into or out of action at intervals. The water is thus allowed to escape from the pump and from beneath the pistons through a direct lateral branch pipe, d', which opens from the discharge-pipe c' of the pump, and is thence directed into the tank b, and provided with a throttle-valve, f'. Hence by opening this valve fully the water discharged from the pump, as well as that in the cylinders e e, will find free escape. Consequently the weight of the spindle, &c., on the hydraulic pistons will be unsupported, and they will descend, forcing the drill into the rock or other strata with a pressure proportioned to the weight of the unsupported parts. By closing the valve partly, however, the water-pressure will become somewhat confined and a slight pressure brought to bear upon the pistons, which will overcome some of the said weight and reduce the pressure on the drill. If the valve be further closed, the weight may be just balanced by the water-pressure, allowing the drill to revolve without advancing; and if closed still further, the spindle will rise with a speed proportioned to the degree of closure. If the valve be fully closed, the frame and spindle will rise till the cross-head d strikes the cross-bar i, when an adjustably-weighted valve, D, on the discharge-pipe c' will open and prevent any unsafe concentration of pressure on the said parts should the valve f' be left inadvertently closed for too long a time. This valve may thus be set to any desired or safe pressure, which cannot be exceeded without allowing the escape of the water, and it hence prevents accidents; and it will also serve to regulate the greatest degree of pressure which may be put upon the drill during the operation of the machine. Thus, if the valve be set to a pressure less than sufficient to lift the frame and spindle, the latter can hence descend to press the drill to its work with just that force represented by the difference between this weight and water-pressure, which may be rendered more or less, according to the adjustment of the said valve.

It may now be observed that this system of hydraulic feed for regulating the pressure on and advance of the drill is peculiarly adapted for its purpose, and enables the action of the drill to be controlled with ease and perfection.

It will be noted that not only can any degree of pressure be put upon the drill, but this pressure is not applied positively, but, so to speak, passively, by the action of gravity, thus allowing the drill to descend into the rock or other strata with a regular passive pressure only as

fast as it can cut its own way, and not forcing it positively to the cut, for it is a well-known fact that while diamond drills cut their way rapidly when revolved, yet they are easily broken and destroyed if forced to the work with a too rapid or concentrated pressure, which is effectually obviated in my machine.

5 I prefer to use with this machine that form of diamond drill patented to me June 22, 1880, No. 229,074; but of course any other suitable form of drill or bit may be used.

10 It will be noted that the water for the hydraulic feeding action is taken from and returned to the tank *b'*, and hence no waste of water results by this circuit. Furthermore, 15 by this arrangement the water used may be purified and freed from grit, used over and over, and completely inclosed in the tank, so as to prevent any grinding action in its course 20 through the pump or other parts of the machine. This arrangement will also allow oil or any other fluid of a good lubricating character to be used instead of water, and thus reduce friction in the pump, &c.

25 Where a constant head of water is available from an elevated reservoir this may be used in lieu of the pump to charge the cylinders *cc*; or this pump may discharge at intervals into an elevated tank, from which the water-column 30 may be led to the cylinders *cc* with the same effect as in the case illustrated.

The several motions of the machine are governed by the action of one operator standing in front of the drill-spindle by the three handles 1 2 3, projecting from the front of the machine, as shown clearly in Figs. 1 and 2. The handle 1 connects with the throttle-valve of the steam-engine, and hence controls the speed of 35 the engine, and consequently the speed of 40 rotation of the drill-spindle. The handle 2 connects to the steam throttle-valve of the pump, and thus controls the speed of the pump, and consequently the speed for raising or lowering the drill, while the handle 3 connects to 45 the throttle-valve *f'* of the water-pressure, and hence controls the lifting or feeding pressure on the drill, as before described. It will be seen that all these handles project in a group 50 from the front of the machine, as seen best in Fig. 1, and in a position convenient to the right hand of the operator when facing the drill-spindle. Hence one operator, while standing in front of the spindle over and alongside the bore, can tell by his experience, by the motion 55 of the drill, the character of the noises or vibration emitted therefrom, the nature of the strata through which the drill is working; and by means of the said handles in said convenient position, and controlling all motions of 60 the machine, the operator can instantly accelerate or reduce any motion of the machine, and apply more or less pressure on the drill in a most easy and certain manner, thus rendering 65 the operation of the machine under the perfect control of one person, and completely adapted to all requirements of actual practice.

Having thus fully described my invention, I claim as new and desire to secure by Letters Patent—

1. A rock-drilling or well-boring machine 70 constructed with a rotary drilling-spindle arranged in vertical position, in combination with a reciprocating engine arranged in horizontal position, with its driving-shaft placed vertical and parallel with the drilling-spindle 75 and directly geared therewith, substantially as herein shown and described.

2. A rock-drilling or well-boring machine having its drilling-spindle supported on hydraulic pistons, in combination with a means 80 of charging the inclosing-cylinder thereof from beneath said pistons with water under pressure, tending to constantly support and lift said pistons, with a valve arranged to confine the water-pressure thereon or allow its escape 85 with more or less freedom, to effect the rise or fall of the said piston or pistons with any desired speed or pressure, substantially as herein set forth.

3. The combination, with a rock-drilling or 90 well-boring machine having its drilling-spindle supported on hydraulic pistons, of a hydraulic pump arranged to charge the cylinders of said pistons, a controllable valve to allow the regulated escape of the fluid from said cylinder and pump, and a tank arranged on the circuit of said pump, with the suction and discharge pipes thereof directed into said tank, substantially as and for the purposes set forth.

4. The combination, in a rock-drilling or 100 well-boring machine having its drilling-spindle supported on hydraulic pistons which control the rise and fall thereof, with means for charging said cylinder with water under pressure in a direction to lift said pistons or piston, 105 and an adjustably-weighted valve arranged to allow the escape of the fluid when the pistons are raised to their limit or when a given pressure is exerted on the pistons, substantially as and for the purposes specified.

5. A rock-drilling or well-boring machine 110 constructed with an engine or motor to drive or rotate the drilling-spindle, with means for producing the vertical movement of the spindle, and a device to control said vertical movement, in combination with a series of distinct operating-handles, 123, controlling each movement, arranged in a group on the front of the machine, adjoining the drilling-spindle, substantially as and for the purpose specified.

6. In a rock-drilling or well-boring machine substantially such as described, the combination, with a vertically-sliding frame supporting the drill-spindle, of the circle of balls or rollers *l*, resting in said frame, and the bearing-rim *k*, fixed to said spindle and resting on said rollers, substantially as herein shown and described.

JOHN ATKINSON.
